OR D 14,960

No. 14,960

Apr. 15, 1884

UNITED STATES PATENT OFFICE.

CHARLES A. MAY, OF TRENTON, NEW JERSEY, ASSIGNOR TO JOSEPH BURROUGHS AND ELIJAH MOUNTFORD, BOTH OF SAME PLACE.

DESIGN FOR ORNAMENTATION OF TABLE-WARE.

SPECIFICATION forming part of Design No. 14,960, dated April 15, 1884.

Application filed October 29, 1883. Term of patent 7 years.

To all whom it may concern:-

Be it known that I, CHARLES A. MAY, of the city of Trenton, county of Mercer, and State of New Jersey, have invented a new and useful Design for the Ornamentation of Articles of Table-Ware, and which is described in the following specification, and shown by the accompanying photographic illustrations.

These illustrations show ten different articles of table-ware to the ornamentation of which my design is applied; but I do not limit myself to the ornamentation of the articles thus shown, as my design can be applied, and I do apply it, to any and all articles comprising a table-service, and also to articles of toilet-ware.

My design consists of the representation of a mass of tropical flowers and plant-leaves on the sides of cover-dishes and toward the end 20 or side of the plates and flat dishes, and of a band of leaves and scrolls in Byzantine curves

about the rims of such plates and dishes, and the covers of the cover-dishes, and the upper portions of the cups composing such ware, such curves having within each of them an open daisy-like flower.

Figure 2 shows a salad-dish with such a mass of flowers painted or printed thereon. Figs. 4 and 10 show articles having the flowers, and also the band. Figs. 3, 5, 8, and 9 show articles having the flowers with the band about the covers. Figs. 1, 6, and 7 show articles with the flowers and also the band about the rim, A showing the flowers, and B the band.

What I claim as my invention, and desire to secure by Letters Patent, is—

In a design for table-ware and like articles, the ornamentation herein shown and described.

CHAS. A. MAY.
